ERNST FLAMMER AND CHRISTIAN KELBER, OF BEILBRONN, GERMANY.

MANUFACTURE OF SOAP.

No Drawing. Original application filed November 16, 1925, Serial No. 69,488. Divided and this application filed August 16, 1926. Serial No. 129,656.

This application is a division of application No. 69,488, filed November 16, 1925.

The well-known soap powders comprising compounds containing active oxygen, more particularly containing alkaline per-salts, are made by mixing dry finely powdered soap and alkaline per-salts in the form of powder with or without addition of other dry washing agents in powder form.

10 These soap powders made of dried soap and per-salts become readily dissociated, as the size of the granules as well as the specific weight of the constituents are different. Moreover the soap in powder-form dissolves 15 quicker than the per-salt when they are employed and there is thus the danger that the less soluble per-salts of greater specific weight settle upon the articles being washed and, forming a concentrated solution, cause 20 a strong local action and thus a damage to the materials.

According to the present process, however, water containing soap is used for the manufacture of soap flakes or soap bands containing alkaline per-salts. The soap with a relatively low water content, for instance from 25 8 to 14% water, are exceedingly brittle when used alone. It appeared to us that it would not be possible to form the soap into thin 30 flakes or the like when adding alkaline per-salts to the soap.

The form of thin flakes or the like is of particular advantage, as it ensures a uniform solution of the soap and of the alkaline per-salts contained therein. In this form it is 35 not possible for perborate granules liberated from the soap envelope to produce a strongly concentrated local bleaching solution which would cause holes to be formed in the articles being washed.

According to the present process soap having a small water content, say from 8 to 14% water, is intimately mixed with compounds in powder form, containing active oxygen, 45 particularly alkaline per-salts, the mixture is then rolled out thin in rolling machines and cut up in a cutting machine into small pieces in flake form. The essential feature of the present process consists in mixing soap having a small water content and alkaline per-salts, and bringing these mixtures into a form 50 which with certainty prevents the constituents becoming dissociated, which would cause damage to the articles being washed, and ensures an exceedingly ready solubility.

The manufacture of flakes or bands of soap mixed with salts particularly alkaline per-salts has certain special advantages, if these flakes or bands are made translucent, as is the case according to various modifications 60 of the present invention. Hitherto it has not been possible to make either non-translucent or translucent bands from such a mixture. The applicants have discovered, that translucent flakes or bands may be made, if the 65 fatty acids required for the manufacture of the soaps contain a fairly large percentage of acids of the formula $C_nH_{2n-2}O_2$ and $C_nH_{2n-4}O_3$. With such an addition of acids a uniform band is formed on the rolls, from 70 which readily soluble, translucent flakes or bands may be produced. Less saturated acids, for instance those of the formula $C_nH_{2n-4}O_2$ are not suitable for use as additions to these soaps, when per-salts, there is 75 a danger of the formation of organic peroxides.

The products obtained with the admixture of the said acids are translucent and elastic and dissolve uniformly and readily. In this 80 way soaps containing considerable quantities of salts or mixtures of salts with a suitable quantity may be made in the form of thin translucent, elastic flakes.

The invention is carried out for instance in 85 the following manner:

1. A soap is made, the fatty acid mixture of which contains lauric and myristic acid along with 35% ricinoleic acid. The soap thus produced is dried, mixed with 20% sodium perborate and rolled in the rolling machine. Translucent flakes are obtained, which are readily soluble, even in cold water.

2. A soap is made, the fatty acid mixture of which contains lauric, myristic and palmitic acid together with 50% erucic acid: this soap is dried and mixed with 15% sodium perborate. After rolling in the rolling machine translucent, readily soluble flakes are obtained.

In place of the one definite salt mixtures of salts particularly alkaline per-salts may of course be used. The selection of the acid to be added (for instance ricinoleic acid or erucic) depends on the kind and quantity of 105 the combined salts particularly alkaline per-salts or mixtures of salts, particularly alkaline per-salts.

Another modification in the manufacture 110 of translucent flakes or bands from a mix-

STABILIZED PEROXIDE SOLUTION

No Drawing. Application filed October 12, 1927, Serial No. 225,834, and in Austria September 16, 1926.

This invention relates to the preservation and use of peroxide solutions. It has for its object the preparation of peroxide solutions which are stabilized against decomposition during transportation and storage and which at the same time contain agents which will activate the action of the peroxide during use.

Peroxide solutions have been stabilized prior to use by the addition of various organic materials such as alcohol, urea, barbituric acid, acetanilid, acet-o-p-phenetidid, and the like. Furthermore various inorganic materials have been added to bleach baths, for example, which tend to conserve the oxygen and activate or catalyze the peroxide action; the oxygen loss from the baths, however, has remained high. In these practices, only the stabilization alone of solutions during transportation etc. has been effected by the additions at the time of manufacture, while the second activating action is secured by additions to the bleach bath, and the like.

I have found that for use in bleaching peroxide solutions may be stabilized by any of the above substances, but that the stabilizer causes a lowering of the bleaching power. On the other hand, I have found that activated peroxide bleach baths often produce good bleaching effects but that the consumption of active oxygen is high.

I have now discovered that peroxide solutions, specifically hydrogen peroxide solutions, can be prepared which are not only stabilized against decomposition during shipment, storage, and dilution precedent to use, but the bleaching action is also activated during use so that the loss of unused oxygen is low. This I accomplish by the addition to the peroxide solution, at the time of manufacture, of one or more of each of a stabilizing and activating substance. I have found during the use of such solutions as for example in bleaching, that the stabilizing and oxygen activating substances act reciprocally on each other to assist in their respective specific actions.

I have found that hydrogen peroxide solutions containing a plurality of such materials, i. e., one or more of each of a stabilizer and

an activator are especially valuable. Hydrogen peroxide solutions containing such combinations of reciprocally acting compounds suffer practically no decomposition, or loss of unused active oxygen from the action of the solid materials which are often permanently bound to the fibers of material to be bleached, and which ordinarily would produce a decided loss by catalytic action. Finally, I have found, that these peroxide solutions have the same chemical action in bleaching as ordinary solutions of peroxide alone; cause very little loss of active oxygen from the actual bleaching process; are stable to shipment and storage in warm climates; do not injure materials to be bleached; may be diluted for use without loss of active oxygen; eliminate the necessity for special additions at the time of preparing a bleaching bath; give better bleaching results with less peroxide consumption; and may be used while containing the same additions in the same proportions for every type of bleaching.

The results mentioned above may be obtained to an extraordinary degree by the simultaneous addition to peroxide solutions of a combination such as sodium pyrophosphate, sodium silicate, and sodium chloride, or of various combinations of sodium pyrophosphate, sodium chloride, chlorinated hydrocarbons, colloidal materials, Turkey red oil, water glass, etc. However, I wish it expressly understood that the present invention is not to be limited to these specific additions nor to the examples given below. On the other hand, any combination of stabilizers and activators for peroxide solutions resulting in a mutual action which increases the power of each during the reaction of the peroxide with other substances, and which produces a stabilizing action on the solution when not in use, should be considered as belonging to the present invention.

The following are given as examples:

Example 1

To a 30% solution of hydrogen peroxide there is added 2.5% of $\text{Na}_4\text{P}_2\text{O}_7 \cdot 10\text{H}_2\text{O}$ and 1% NaCl , the normal weakly acid reaction is
